UNITED STATES PATENT OFFICE.

EDMUND JOSEPH KANE, OF CHICAGO, ILLINOIS, ASSIGNOR TO WEBSTER ELECTRIC COMPANY, OF RACINE, WISCONSIN, A CORPORATION OF WEST VIRGINIA.

ELECTRIC IGNITER FOR EXPLOSIVE-ENGINES.

1,204,573.

Specification of Letters Patent. Patented Nov. 14. 1916.

Application filed February 2, 1910. Serial No. 541,428.

To all whom it may concern:

Be it known that I, EDMUND JOSEPH KANE, a citizen of the United States, residing at Chicago, in the county of Cook and State of Illinois, have invented certain new and useful Improvements in Electric Igniters for Explosive-Engines, of which the following is a full, clear, and exact specification.

10 The invention relates to improvements in electric-igniters for explosive engines.

The object of the invention is to provide an electric igniter mechanism with novel and improved means for producing the 15 spark for firing the charge.

A further object of the invention is to provide in a device of the character described improved means by which when the exhaust valve is held open during the operation of the engine by the speed governor mechanism and no charge in the cylinder is to be exploded, the igniter mechanism is rendered inoperative and consequently the generator consisting of the oscillating or rotatable armature or inductor remains idle and a spark is not produced and as a consequence the resulting wear upon the moving parts and the loss of energy required to generate a useless spark is avoided.

20 30 A further object of the invention is to provide in a device of the character described, direct and positively operating means for imparting movement to the oscillating armature or inductor, which preferably comprises the movable part of the generator.

To the attainment of these ends and the accomplishment of certain other new and useful objects, as hereinafter described, 40 shown in the accompanying drawings forming a part of the specification, and finally pointed out more specifically in the appended claims, the invention is directed.

In the said drawings, Figure 1 is a side 45 elevation of an explosive engine with the invention attached and having parts of the igniter mechanism shown in section and other parts shown in broken lines in order to more fully disclose the details of construction of the igniter mechanism and one manner of attaching the invention to an explosive engine. Fig. 2 is a detail plan view of the igniter mechanism with the walls of the cylinder of the explosive engine to which it is 55 attached in section. Fig. 3 is an enlarged

detail view of the igniter parts similar to the view in Fig. 1, but showing in dotted lines the relative movements of the exhaust valve operating rod, and the igniter operating means by which the igniter mechanism 60 or generator is rendered inoperative and a spark not produced when no charge is to be exploded in the cylinder because of the action of the speed governor through the exhaust valve operating means on the generator 65 of Fig. 2.

Similar characters of reference indicate similar parts throughout the several views.

1 is the engine cylinder, and 2 the main 70 frame.

3 is the engine base.

4 is the fly-wheel on shaft 5 provided with a crank 6 operated by connecting rod 7 pivoted to the piston on the interior of the cylinder 1 in the usual or any desired manner.

The engine cylinder 1 is provided with the usual side opening adapted to receive the usual igniter block 8 which is provided with an inner extension 9 fitted through the opening and extending into the cylinder 1. In the horizontal opening through the block 8 extends a stationary electrode 10 which is preferably insulated from the igniter block 8 by suitable insulating material in the usual 80 manner and not herein specifically shown, since it is the common practice to insulate the stationary electrode from the igniter block rather than the movable electrode. Outside the block 8 on the electrode 10 is 90 provided means for the securement to the electrode 10 of the wire 11, such means preferably comprising a threaded outer end on the electrode 10 and the two threaded chamfered or polygonal nuts 12 and 13, between 95 which one end of the wire 11 may be secured.

Secured to the igniter block 8 and preferably cast integral therewith is an arm 14 extending for a short distance approximately 100 parallel with the outer wall of the cylinder 1 and provided at its forward extremity with the angular bearing portion 15 into which the shaft 16, on which is carried the armature or inductor, is journaled. The armature or inductor may be of any desired type as well as the construction of the field of the igniter but the preferred form is an armature or inductor of the form shown only in dotted lines as indicated by the ref. 110

erence character 17 in Fig. 1 of the drawings, which, although not specifically shown may consist of masses of laminated iron suitably joined together and of approximately 5 the form shown in dotted lines in Fig. 1 and being mounted to oscillate with shaft 16, will, in a well known manner, produce rapid periodic reversals in the magnetic polarity of the cores 18 and 19 indicated in broken 10 lines on Fig. 1 and will in a well known manner set up alternate currents in the coils surrounding them. The wound cores 18, 19 may consist of projections from the laminated iron plates indicated at 20, 21, which 15 at their upper and lower extremities are joined by the magnet plates 22, 23.

While I have herein shown the invention applied to one specific form of generator or magneto and have to an extent shown and 20 described the details of construction of such magneto or generator, it will be apparent that the invention may be applied by those skilled in the art to any type of magneto or generator whether of the oscillating type 25 or armature or inductor or whether of the constantly rotating type of armature or inductor. It will also be apparent that the invention may equally be applied to magnetos or generators for furnishing electrical 30 ignition whether the armature or moving part is of the wound type instead of the laminated metal or whether the field be of the ordinary form of winding.

The laminated cores 18, 19, may be wound 35 in the manner common to this type, one end of the winding indicated by 24 being connected to the supporting block 25 in contact with sleeve 15 and secured thereto by set screw 25^a, which completes the circuit to the 40 bearing block 8 and the movable electrode 26, which is also journaled in bearing block 8 and extends to the outside of the block, being provided at its outer extremity with the crank arm 27 and held normally in such 45 position that the electrodes 10 and 26 are normally in contact with each other by means of the torsion spring 28, one end of which is secured to the igniter block 8 and the other end in engagement with the 50 crank arm 27. The wire 11 already referred to as in contact with electrode 10 leads directly to the wound core 19, thus completing the electrical circuit. To the supporting block 25 is secured the laminated field members 20, 21, which carry the wound cores 18, 55 19. The end of the crank arm 27 on the movable electrode 26 is provided with an adjustable screw 29 provided with a lock nut and having a head at its lower extremity 60 for engagement with the oscillating member 30, which is secured to rotate with the oscillating shaft 16 carrying the armature or inductor 17. The oscillating member 30 secured to the armature shaft 16 is provided 65 with horizontally extending arms, the ex-

tremities of which are in engagement each with one end of coil springs 31, 32, which have their outer extremities secured to brackets 33, 34, extending laterally from the laminated field members 20, 21. The 70 springs 31, 32 normally exert a tension on the oscillating member 30, thus holding the armature or inductor 17 in its normal position and offering elastic resistance to the rotation of the inductor or armature, which 75 in order to rotate or oscillate must move with the oscillating member 30 through the medium of the armature shaft 16, to which both are secured. The oscillating member 30 is provided with a vertically extending 80 projection or finger as indicated at 35 adapted for engagement by the reciprocating member 36 for the purpose of oscillating the armature or inductor 17 against the tension of springs 31, 32. The extension 15 carried 85 on the igniter block 8 through the connecting portion 14 is provided with an extending branch as indicated at 37, the outer extremity of which carries a grooved roller or sheave 38, which serves as an anti-friction 90 bearing and support for the reciprocating member 36, the free end of which adjacent the grooved roller or sheave 38 is adapted normally to engage the finger 35 to oscillate the armature or inductor. Reciprocating 95 movement is imparted to the member 36 preferably from the crank shaft 5 of the engine, and a convenient way of accomplishing this purpose is to secure to crank shaft 5 a gear as indicated at 40, which meshing 100 with the gear 41, is of suitable size to impart the desired speed to the igniter whatever the character of the engine.

In the present embodiment of the invention, as shown particularly in Fig. 1, the 105 engine is of the single cylinder four-cycle type, the gears 40 and 41 being of proper proportions to impart the desired speed to the shaft 42 and gear 41 for operating the exhaust valve rod, as indicated at 43, which 110 is accomplished by the action of the eccentric cam 44 keyed on shaft 42 and bearing against the anti-friction roller 45 carried at the upper extremity of the pivotal support 46 of the exhaust valve operating rod 43. The igniter operating member 36 may be operated from the shaft 42, which also carries the eccentric cam 44 in any desired manner, a convenient form being indicated 115 in the drawings in Fig. 1 consisting of an eccentric secured to shaft 42 and carrying a strap 47 secured to the forward extremity of the igniter operating member 36.

It is well known in this art that means such as just described may be used for operating the exhaust valve operating rod and it is equally well known in explosive engines that centrifugal governors may be employed on moving parts of the engine in order to control the speed of the engine by 120 125 130

5 preventing the closing of the exhaust valve when the engine reaches or exceeds the given speed. In explosive engines of the type herein shown, the piston is employed as a
 10 pump for drawing the explosive material into the cylinder but when the exhaust valve of the engine is held open automatically the action of the piston within the cylinder in creating a vacuum will be to cause the air to rush into the cylinder when the exhaust valve is open, following the lines of least resistance, so that a charge will not be drawn into the cylinder when the exhaust valve is open and consequently there will be no explosion take place in the cylinder. Heretofore it has been the practice in the use of igniters to connect them up positively with the engine so that the igniter runs constantly with the engine and a spark is produced at each cycle of operation of the engine whether a charge of explosive has been drawn into the cylinder or not. If, therefore, the engine has reached or exceeded a given speed and the explosion has been cut out by reason of the action of the governor due to the excessive speed, no explosion can take place until the speed has been reduced to or below the given degree and yet the igniter mechanism must continue to operate
 20 and the spark is wasted together with the energy necessary to create it and the igniter mechanism has been subjected to the wear incident to such operation for no useful purpose. It is to obviate this condition of useless wear on the igniter mechanism that is one of the special purposes of this invention, as stated, and it is not important what specific means for governing the speed of the engine be employed but the common
 25 form of reciprocating exhaust valve operating rod has been shown as commonly operated on four-cycle engines and this is further shown under the control of an ordinary centrifugal governor comprising pivoted
 30 weighted members 50, 51, secured to the flywheel 4 or the crank shaft 5 of the engine and normally held in a given position by suitable springs 52, 53, which may be adjustable in order to vary their tension in a well known manner not necessary to describe for the purposes of illustrating the present invention. These spring controlled pivoted members 50, 51, may be connected with a suitable member slidably mounted on
 35 crank shaft 5, which preferably has an exterior cone shape and against which bears one end of the latch 54 which is pivoted at 55 on the main frame of the engine and has one end, as indicated at 56, adapted to engage with a notched member 57 on the exhaust valve operating rod 43. The usual operation of this form of governor is that, with the springs 52, 53 adjusted to have a given tension when the speed of the crank 40 reaches or exceeds a given speed, the op-

eration of the governor will cause the end 56 of the latch to be depressed so that it will engage the notched member 57 on the exhaust valve operating rod 43 and prevent the return of this rod when released by cam 44 and in this manner hold open the exhaust valve preventing further explosions of the engine because preventing the drawing in of a charge until the speed of the crank shaft falls below the given speed when the spring controlled members 50, 51 on the governor will act to release the exhaust valve operating rod and permit the exhaust valve to close, which will then cause the action of the piston to draw in a charge of explosive for the use of the engine.

It is obvious that even though the reciprocating member 36 which is shown as constantly operating from the crank shaft of the engine shall operate the igniter mechanism, the spark produced will be wasted if the exhaust valve is not closed so that a charge of explosive is provided within the cylinder. It is found by experience that it is very desirable to avoid all the wear and tear possible on the igniter mechanism. In order therefore that the igniter mechanism may be rendered inoperative and consequently no spark produced when there is no charge in the cylinder to be exploded by reason of the exhaust valve being automatically kept open due to the engine having passed a given speed and because of the governor control over the exhaust valve, I provide means for automatically stopping the operation of the igniter mechanism under the control of the exhaust valve operating means. In the present embodiment of the invention the exhaust valve being under the control of the exhaust valve operating rod 43 I secure to the rod 43, in any suitable manner, a support 60 carrying at its upper extremity a suitable anti-friction roller 61. In order that the igniter operating member 36 may be properly timed to release the spring controlled igniter mechanism, the rod 36 is provided with a wedge block 62 adjustably secured thereto by set screw 63. By this means the timing of the igniter mechanism is secured. Another wedge block 64 similar to the block 62 but having its inclined face in the opposite direction is also adjustably secured on the igniter operating member 36, as indicated at 64, and this member is adjustably secured to the member 36 by set screw 65. The operation of the exhaust valve cut out in its relation to the igniter mechanism is best seen from an inspection of the parts depicting the exhaust valve operating rod 43 and the igniter operating member 36 at the extremes of their movements as indicated by the full and dotted lines representing those parts, as shown in Fig. 3.

The operation of the mechanism or as

much thereof as pertains to the features of novelty herein described and claimed is as follows: The operator, desiring to start the engine, may turn the same in the usual manner, thus drawing in the charge of explosive into the cylinder. The operation of starting the engine will also impart movement to the igniter or generator operating member 36 through the gears 40 and 41, the 5 shaft 42 and the eccentric secured thereto which operates the member 36. The movement of the member 36 causes its extremity adjacent the igniter mechanism to engage the upwardly extending arm 35 near its upper 10 extremity and thus rotate the member 30, the shaft 16 and the armature or inductor of the generator carried thereon against the tension of springs 31, 32. This rotation or 15 oscillation of the inductor or armature of the generator will cause a current to be generated which will pass through the electrodes 10 and 26 in the circuit already described. The adjustable wedge block 62 under control of set screw 63 on the igniter 20 operating member 36 may be adjusted so that the forward end of the member 36 will become disengaged from the arm 35 on the oscillating member 30 at the time the current passing through the electrodes 10 and 25 26 is near its maximum strength. The sudden release of the oscillating member 30 being under the control of the springs 31, 32 will cause it to be returned to normal position, as shown in all of the figures, under 30 considerable momentum which will cause the extremity of the oscillating member 35 30 adjacent the crank arm 27 to strike the adjustable screw-threaded member 29. This will rotate the crank arm 27 against the action of spring 28 and will at the same 40 time separate the movable electrode 26 from 45 the stationary electrode 10. The current being at about its maximum strength, as stated, a spark will then pass between the electrodes 10 and 26.

The engine having reached or passed a 50 given speed by reason of which the governor mechanism has locked the exhaust valve operating rod 43 against closing the exhaust valve, the support 60 on the exhaust valve operating rod 43 will be carried to the position indicated in dotted lines in Fig. 3 by which the antifriction roller 61 carried thereby will pass under the adjustable wedge block 64 and operate the igniter operating member 36 to the position indicated in 55 dotted lines also in Fig. 3. In this position it will be seen that although the igniter operating member 36 continues to operate it will be held in a position where its operation will not affect the igniter mechanism or 60 generator which will remain inactive until 65

the exhaust valve operating rod 43 is returned to normal.

By means of the mechanism as described, it will be seen that the igniter mechanism or generator including the spring controlled 70 oscillating member 30, the armature shaft 16 together with the armature 17 and the movable electrode will all be cut out and remain inactive at all times when the engine is running above normal speed and it 75 is not desired to ignite a charge in the cylinder. It will also be seen that the arrangement of the parts as described for operating the oscillating form of igniter or generator herein shown is exceedingly simple and direct and that by directly operating the oscillating means controlling the armature or inductor through the medium of the reciprocating member 36 I provide an exceedingly simple and durable mechanism that 80 is certain in its operation and not liable to get out of order, and furthermore the movable parts of the igniter being rendered inactive at all times when the exhaust valve 85 is open, there is no useless current generated 90 in the igniter as is the case with the igniters positively operated from the crank shaft of the engine without means for cutting out the operation of the igniter mechanism under the control of the exhaust valve 95 operating means or the speed governor.

In order that the invention might be fully understood the details of the preferred embodiment thereof have been thus specifically described but it is not desired to be limited to the exact details of construction thereof, for it will be apparent that many modifications may be made by those skilled in the art without departing from the purpose and spirit of the invention, and what I claim is— 105

1. In an explosive engine, the combination with a magneto, of means for operating the magneto by the running of the engine, a speed governor operated by the engine, and means under the control of the speed governor for rendering the magneto operating means inoperative when the engine passes or exceeds a predetermined speed. 110

2. The combination in an explosive engine having a speed governor, and an exhaust valve operating rod operatively connected with the speed governor, of a magneto, means for operating the magneto by the running of the engine, and means adapted to be operated by the movement of the exhaust valve operating rod for rendering the magneto operating means inoperative. 115 120

3. In combination with an internal combustion engine, a speed governor associated with the engine and operatively connected therewith, ignition mechanism for said engine comprising make and break spark electrodes and a magneto, means operated by the engine for effecting the operation of both the magneto and spark electrodes in 125 130

timed relation one to the other, and mechanism controlled by said speed governor for rendering said engine operated means incapable of effecting the operation of the magneto and spark electrodes whenever the engine passes or exceeds a certain predetermined speed.

4. An internal combustion engine of the hit and miss type having an exhaust valve, 10 an exhaust valve operating rod and a speed governor in operative relation to said exhaust valve operating rod arranged to shift the latter to hold the exhaust valve in open position whenever the engine exceeds a certain predetermined speed, in combination with an igniter comprising make and break electrodes, a magneto for supplying ignition current to said igniter, a reciprocating push rod driven by the engine for effecting actuation of the magneto and igniter electrodes together with means operated by the exhaust valve operating rod for rendering the reciprocating push rod incapable of actuating the magneto and igniter electrodes whenever, when the engine exceeds a certain pre-

determined speed, the exhaust valve operating rod and the governor coöperate to hold the exhaust valve in open position, as aforesaid.

5. In combination with an internal combustion engine, a speed governor driven from the engine, ignition mechanism for said engine comprising an igniter and a magneto for supplying ignition current to said igniter, actuating mechanism driven by the engine for effecting the operation of the magneto, and devices controlled by the speed governor for rendering said actuating mechanism incapable of effecting the operation of the magneto whenever the engine 30 passes or exceeds a certain predetermined speed.

In testimony whereof I have signed my name to this specification, in the presence of two subscribing witnesses, on this 22nd day 35 of January, A. D. 1910.
